DESIGN FOR AN EDUCATIONAL DESK

Henry S. Wilson, Brooklyn, N. Y.

Application January 24, 1941, Serial No. 98,357

Term of patent 14 years

To all whom it may concern:

Be it known that I, Henry S. Wilson, a citizen of the United States and resident of Brooklyn, New York, in the county of Kings and State of New York, have invented a new, original, and ornamental Design for an Educational Desk, of which the following is a specification, reference being had to the accompanying drawing, forming a part thereof.

Fig. 1 is a perspective view of an educational desk, showing my new design.

Fig. 2 is a top plan view of the same.

Fig. 3 is a side elevational view of the same.

I claim:

The ornamental design for an educational desk, as shown,

HENRY S. WILSON.
